UNITED STATES PATENT OFFICE.

ELMER E. F. CREIGHTON, OF SCHENECTADY, NEW YORK, ASSIGNOR TO GENERAL ELECTRIC COMPANY, A CORPORATION OF NEW YORK.

FAULT-LOCALIZER.

1,105,883.

Specification of Letters Patent.

Patented Aug. 4, 1914.

Application filed May 14, 1913. Serial No. 767,542.

To all whom it may concern:

Be it known that I, ELMER E. F. CREIGHTON, a citizen of the United States, residing at Schenectady, county of Schenectady, State 5 of New York, have invented certain new and useful Improvements in Fault-Localizers, of which the following is a specification.

My invention relates particularly to cable 10 transmission systems and the object of my invention is to localize faults in the cable.

In cable transmission systems it is common practice to inclose the cable in a metallic sheath, often of lead. I propose to divide the metallic sheath into sections, preferably, by inserting insulating material transversely to the length of the cable at more or less equal distances apart, these insulating portions insulating the sections from 20 each other. The sheath and cable, as a whole, is insulated from the ground, except that each section of the metallic sheath is supplied with one or more connections to the ground. I provide an indicating means 25 related to each connection, to indicate the passage of current over the respective connections. Now when a fault develops, as by an arc from one of the conductors of the cable, current passes between the conductor 30 and the sheath, and through the connection to that section of the sheath to ground. In case such a fault develops not only will that connection carry current which is attached to the section of the sheath to which 35 the arc forms, but every other connection to every other section will carry charging current to their respective sections. However, the connection to the faulty section will of necessity carry a current equal to 40 the sum of all the currents carried by the other connections and this condition makes it possible to pick out the faulty section. This differentiation may be obtained by setting the indicators to operate at a certain 45 minimum value, which value is greater than the value of the charging current of a section. Only the connection to the faulty section carries a current sufficient to operate an indicating means and hence the indicating means relating to the faulty section is 50 the only indicating means operated. I prefer, however, to combine all or a plurality of the indicating means in such a way that

the greater strength of the current on the connection to the faulty cable prevents the 55 operation of the indicating means related to the other connections.

My invention will be better understood from the specific construction subsequently 60 described.

In the accompanying drawings which form a part of my specification the single figure illustrates a part of a cable system of distribution involving my invention.

The sections of the metallic sheath of a 65 part of the cable of the system are illustrated at 10, 11, 12 and 13, these sections being insulated from each other by the insulating bodies 14 transverse to the extension of the cable. Connecting the respective sections of the sheath to form a conducting path to ground are connections 15, 16, 17 and 18. In each of the connections I have provided a transformer 19, the secondary of which supplies energy to the respective 75 indicator. The indicators may assume a variety of forms, for example, at 21 is shown one form of indicator. The solenoid 25 of this indicator is connected to the secondary of the respective transformer 19. The core 80 26 of this solenoid carries a hook member 27, normally out of engagement with the ring 22. The ring 22 is movable vertically and is guided by the arm 23 sliding in a fixed member 24, and the ring 22 is normally 85 held in the position illustrated by the spring 28. A battery 29 is connected to the arm 23 at one side and at the other side through the bell or other signal 20 to the hook member 27. Now in case a fault develops in the 90 section 10 of the sheath of the cable, current flows to or from the ground over the connection 15, and hence through the respective transformer 19. The solenoid 25 is energized and providing the strength over 95 the connection 15 is sufficient, the core 26 is pulled into the solenoid and contact is made between the hook member 27 and the ring 22. A circuit is thus completed through the battery 29 and the indicator 20 showing 100 that the section 10 is faulty. Now, as before pointed out, if each section of the cable is provided with such an indicating means or with similar indicating means, for example such as is shown at the right of 105 the figure and later described, all the indi-

5 cators tend to operate on the development of a fault, unless special provisions are made. Such provisions may consist in requiring that the cores be drawn into the 10 respective solenoids only when the current in the solenoid exceeds a certain minimum value. This value may be such that it is reached only when the fault develops in the section to which the respective connection is made, the charging currents to the healthy sections being below the minimum value required to operate the indicators. I prefer, however, to combine or interlock the indicators in such a way that the indicator 15 responding to the greatest current, prevents the operation of other indicators. Such a combination of indicating means I have shown at 30. The respective transformers 19 in the connections 16 and 17 supply the 20 solenoids 35 and 36. These solenoids control the cores 37 and 38 which carry the hook members 39 and 40 respectively. The cores are also connected in this case through their hook members 39 and 40 to the springs 25 41 and 42 respectively, the other ends of the springs being held stationary. A ring 31 provided with a guiding arm 32 sliding in a stationary member 33 and normally held in one position by the spring 34, is 30 adapted to be acted upon by both hook members 39 and 40.

A signal means 20 is provided for each hook member 39 and 40, the circuit through the signal means being completed by the engagement of the respective hook member with the ring 31, as pointed out with reference to the indicator 21. Assuming that an arc forms between one of the conductors of the cable and the section 12 of the 35 sheath:—Current is carried by the connection 17 and also by every other connection to every other section of the sheath of the cable. The current in the connection 17 is however approximately equal to the sum of the currents in all the other connections. 40 The result is that the solenoid 36 is more highly energized than the solenoid 35 and the core 38 is pulled farther into the solenoid 36 against the tension of its spring 42, than is the core 37 into its solenoid 35 45 against the tension of its spring 41. The hook member 40, therefore, picks up the ring 31 and pulls it against the tension of its spring 34 beyond the reach of the hook member 39. The circuit is thus completed through the respective signal member 20 connected to the hook member 40, but is uncompleted through the signal means 20 connected to the hook member 39. If desired 50 this particular differentiating indicating means may be combined with a means of a type similar to 21 first described: Thus at 50 I have shown an indicator including a solenoid 51 controlling the core 52 operating in 55 its turn the lever 53. This controls the cir-

60 cuit through the wires 54 and the respective signaling means 20. It is necessary as before pointed out to provide that the core 52 shall be drawn into its solenoid 51 only when 65 that solenoid carries a current of at least a definite minimum value. When such an indicating means is combined with an indicating means similar to 30, it is also necessary 70 that the solenoids 35 and 36 pick up their cores only when carrying currents of at least 75 the same minimum value. If desired, a number of the signaling means 20 may be assembled at one station by using pilot wires, as shown in one instance at 54. For 80 the purpose of changing the character of, or controlling, the current on the connections, it may in some instances be desirable to insert resistance 60 in the connections.

What I claim as new and desire to secure by Letters Patent of the United States, is:

1. The combination with a system of distribution including a cable carrying conductors and having a metallic sheath divided into sections insulated from each other, of a connection between a section of the sheath 90 and ground and means for indicating the passage of current over said connection.

2. The combination with a system of distribution including a cable carrying conductors and having a metallic sheath divided 95 into sections insulated from each other, of a connection between each section of the sheath and ground and means related to each connection for indicating the passage of current over the respective connections.

3. The combination with a system of distribution including a cable carrying conductors and having a metallic sheath divided into sections insulated from each other, of a connection between each section of the sheath and ground and means related to each 105 connection for indicating the connection carrying the greatest current.

4. The combination with a system of distribution including a cable carrying conductors and having a metallic sheath divided into sections insulated from each other transversely to the extension of the cable, of a connection between each section and ground and means related to each connection 110 for indicating the connection carrying the greatest current.

5. In combination with a cable having a plurality of conductors, a metallic sheath surrounding said cable divided into sections, 115 said sections being insulated from each other, of a conducting path from each of said sections to ground, and means operatively related to each conducting path for indicating the passage of current in said path.

6. In combination with a cable having a plurality of conductors, a metallic sheath surrounding said cable divided into sections which are insulated from each other, and a 125

connection to ground from each of said sections, of an electroresponsive device operatively related to each of said sections for indicating the connection having the greatest 5 current flow whereby a fault between said conductors and any of said sections is selectively determined.

In witness whereof, I have hereunto set my hand this 12th day of May, 1913.

ELMER E. F. CREIGHTON.
